(57) **CLAIM**

The ornamental design for a spotlight, as shown and described.

DESCRIPTION

FIG. 1 is a right side perspective view of the spotlight design;

FIG. 2 is a left side perspective view thereof, but with the foldable carrying handle in an alternate position;

FIG. 3 is a top plan view of FIG. 1;

FIG. 4 is a bottom plan view thereof;

FIG. 5 is a right side view thereof;

FIG. 6 is a left side view thereof, but with the handle position of FIG. 2;

FIG. 7 is a front plan view thereof, but with the handle position of FIG. 1;

FIG. 8 is a rear plan view thereof, but with the handle position of FIG. 2;

FIG. 9 is an exploded left side view of the removable battery feature thereof, but with the handle position of FIG. 1;

FIG. 10 is an exploded rear perspective view of the removable battery and battery bay portion thereof, but with the handle position of FIG. 2; and,

FIG. 11 is an enlarged perspective view of the removable battery and charging port thereof but shown in an open position and separately for clarity of illustration.
